UNITED STATES PATENT OFFICE

148,594

DESIGN FOR AN ELECTRIC HEATER

Carl W. Sundberg and Montgomery Ferar, Detroit, Mich., assignors to The Swartzbaugh Manufacturing Company, Toledo, Ohio, a corporation of Ohio

Application July 20, 1946, Serial No. 131,752

Term of patent 14 years

(Cl. D81—10)

To all whom it may concern:

Be it known that we, Carl W. Sundberg and Montgomery Ferar, citizens of the United States, residing at Detroit, in the county of Wayne and State of Michigan, have invented a new, original, and ornamental Design for an Electric Heater, of which the following is a specification, reference being had to the accompanying drawings, forming a part thereof.

Figure I is a front perspective view of an electric heater showing our new design.

Figure II is a rear perspective view of the electric heater shown in Figure I.

Figure III is an end view in elevation and on a greatly reduced scale of the electric heater shown in Figures I and II.

The dominant features of our design reside in the portions shown in full lines,

We claim:

The ornamental design for an electric heater, as shown and described.

CARL W. SUNDBERG.
MONTGOMERY FERAR.
